(57) CLAIM

The ornamental design for a pet grooming blade tray as shown and described.

DESCRIPTION

FIG. 1 is a front perspective view of the pet grooming blade tray of the instant invention;

FIG. 2 is a right side elevation view thereof;

FIG. 3 is a left side elevation view thereof;

FIG. 4 is a front view thereof;

FIG. 5 is a back view thereof;

FIG. 6 is a top view thereof; and,

FIG. 7 is a bottom view thereof.

The broken lines in the figures show portions of the pet grooming blade tray which form no part of the claimed design. The post shown in broken lines in FIGS. 1 through 5 show environment and form no part of the claimed design.
